UNITED STATES PATENT OFFICE.

JOHN A. CLARK, OF WORCESTER, MASSACHUSETTS, ASSIGNOR TO CROMPTON & KNOWLES LOOM WORKS, OF SAME PLACE.

ELECTRIC WARP STOP-MOTION FOR LOOMS.

SPECIFICATION forming part of Letters Patent No. 669,620, dated March 12, 1901.

Application filed December 20, 1900. Serial No. 40,478. (No model.)

To all whom it may concern:

Be it known that I, JOHN A. CLARK, a citizen of the United States, residing at Worcester, in the county of Worcester and State of Massachusetts, have invented certain new and useful Improvements in Electric Warp Stop-Motions for Looms, of which the following is a specification.

My invention relates to electric warp stop-motions for looms, and more particularly to a supplemental attachment or mechanism to be combined with or applied to any well-known style of electric warp stop-motion for looms.

15 The object of my invention is to provide a supplemental attachment or mechanism of very simple construction and operation adapted to be combined with any ordinary style of electric warp stop-motion for looms by means 20 of which the electric current can be temporarily broken, if desired, by the operator at any time during the operation of weaving, but especially after one or more threads have been tied up, making a slack in said threads, 25 this slack heretofore causing the loom to stop again through the operation of the electric warp stop-motion, the same as if a warp-thread was broken.

By means of my supplemental attachment 30 or mechanism, consisting, broadly, of a spring-actuated latch or lever combined with an electric warp-stop-motion mechanism, I am enabled to prevent the automatic operation of the warp-stopping mechanism until 35 the slack in the loose threads, above referred to, has been taken up in the ordinary process of weaving, as will be hereinafter fully described.

I have shown in the drawings my supplemental attachment or mechanism for breaking 40 the electric current combined with a well-known style of electric warp stop-motion for looms which is shown and described in United States Patent No. 637,234, of November 21, 45 1899; but it will be understood that my supplemental attachment or mechanism for breaking the electric current may be combined with or applied to any other style of electric warp stop-motion for looms.

50 Referring to the drawings, Figure 1 is an

end view of a portion of a loom, showing parts of the patented electric warp stop-motion above referred to sufficient to illustrate the construction thereof and my supplemental attachment combined therewith. Fig. 2 corresponds with the parts shown at the left in 55 Fig. 1, except that my supplemental attachment is shown in its opposite position when the electric current is broken. Fig. 3 is an edge view of the parts shown in Fig. 2 looking in the direction of arrow *a*, same figure. Fig. 4 shows a front view of my supplemental attachment looking in the direction of arrow *b*, Fig. 5. Fig. 5 is an edge view looking in 60 the direction of arrow *c*, Fig. 4; and Fig. 6 corresponds to Fig. 5, but shows the attachment 65 in its outer position when the electric current is broken. Figs. 4, 5, and 6 are shown on an enlarged scale.

In the drawings, Fig. 1 corresponds with 70 Fig. 1 of the Patent No. 637,234, above referred to, and the construction and operation of the electric warp stop-motion shown correspond with the construction and operation of the electric warp stop-motion shown and 75 described in said patent, except that my supplemental attachment is combined therewith, as will be hereinafter described, to break the electric current when desired, and therefore it will only be necessary to briefly describe 80 the electric warp stop-motion shown in the drawings.

In the accompanying drawings the same reference-figures are used as in the drawings of said patent.

85

1 is the loom side or frame. 2 is an angular bracket secured to the frame. A corresponding bracket is secured to the opposite side of the loom. (Not shown.) To the upper end of the bracket 2 is adjustably 90 secured by a bolt 21 a bracket 22, and to the upper end of said bracket 22 are secured the ends of a pair of lease-rods 24. The usual shipper 28 is formed of spring metal, as is customary, and is secured at its lower end to 95 the front of the frame 1, as shown in Fig. 3.

29 is the usual notched plate, by means of which the shipper 28 is guided and also locked in position in the notch to set the loom in motion in the usual way through the belt- 100

shipper 30 and its operating-lever 31, the latter being forked at its outer end to loosely engage the shipper 28, as shown in Fig. 3.

The bracket 32 is bolted to the loom side 1 at the inner side of the shipper, and said bracket supports the magnet box or case 33, in which is located an electromagnet 34. At the upper front corner of the box or case 33, in suitable bearings 35, is pivoted an armature-lever 36, the inner end of which supports an armature 37 and the outer end of which may have a series of small holes 38 therein.

Loosely hung and adapted to swing on a stud 43, that projects horizontally from the side of the frame 1 below the guide-plate 29, is an L-shaped knock-off lever 44, the lower horizontal end 44' of which projects laterally behind the shipper 28 when the shipper is in engagement with the notch in the guide-plate 29. In the lower part of the knock-off lever 44 is pivoted a gravity-latch 46, the free end of which extends inwardly and is provided with a notch or shoulder 47. A wire connector or link 49 connects the latch 46 with the armature-lever 36, so that there will be a unity of motion between the latch 46 and the armature-lever 36.

It will be obvious that if the magnet attracts the armature 37, as when the circuit is completed, the armature-lever 36 will rise at its outer end and cause a similar movement of the latch 46, which being moved into the path of the lay (not shown) is struck thereby on its forward movement and, together with the knock-off lever 44, is forced forward or toward the front of the loom, so that said knock-off lever 44, striking the shipper 28, will disengage it from the notch in the guide-plate 29 and permit it to immediately swing forward and operate the belt-shipper 30 to stop the loom in the well-known way.

The battery 50 is located in a convenient place, and from one of the poles may lead the insulated circuit-wire 51 and from the other the insulated circuit-wire 52, which lies between the flanges of the frame 1 and is supported where necessary by suitable eyes 53. The wire 51 passes to the magnet 34 and the wire 52 passes through a tubular bolt 5 and is secured to a binding-post (not shown) back of the bracket 2, which post is connected with the metallic contact-roll. (Not shown.)

All of the above-described parts correspond to similar parts shown and described in said Patent No. 637,234, to which reference is here made for a more detail description of the same, if desired.

I will now describe my improvements, consisting of a supplemental attachment or mechanism, combined with the parts above described, to break the electric current when desired and prevent the operation of the electric warp-stop mechanism.

In the patent above referred to, No. 637,234, there is a stud 39 in front of the magnet box or case, which has a stationary contact-spring

40 thereon and extending laterally therefrom in such a position with relation to the shipper 28 as to have an electric contact therewith when said shipper is thrown outward from and held in the locking-notch of the guide-plate 29 and the loom set in operation. When the shipper is in its outward position, as above described, and in engagement with the contact-spring 40 of said patent, the electric current, which passes through the shipper 28, the loom-side 1, bracket 2, and circuit-rods (not shown) which guide the drop-bars, is completed by a drop-bar on one of the warp-threads dropping into contact with the metallic roll 10, (shown in said patent,) and there is nothing to prevent the completing of the circuit, and consequently the stopping of the loom when this happens. To prevent the completing of the circuit and the stopping of the loom, as above described, if desired, in case of slack in any of the tied-up warp-threads or for any other cause, I provide a spring-actuated latch or lever 76, of metal or some conducting material, which is pivoted on a stud 75, fast in a stand 32" on an extension 32' of the bracket 32. The latch 76 has at its upper end a screw-eye 77, to which is attached one end of a spiral spring 78. The other end of said spring is attached to a screw-eye 79 on the extension 32' of the bracket 32. The screw-eye 79 is in such a position relative to the axis of the latch 76 that the spring 78 will act to hold the latch in its forward position in contact with the shipper 28, as shown in Fig. 5, or in its opposite position out of contact with the shipper 28, as shown in Fig. 6. The pivotal motion of the latch 76 is limited by two pins 80 and 80', extending out from the hub 76' of the latch 76 on opposite sides of the pin 81, fast in the stand 32', said pins 80 and 80' coming in contact with the pin 81. An insulated circuit-wire 42 leads from a pole in the magnet 34 to a binding-post 82 on the hub 76' of the latch 76. The latch 76 or the bracket 32, on which it is supported, is insulated from the loom-frame 1, so that the current cannot be carried through said frame.

It will be seen that the latch 76 takes the place of the contact-spring 40 referred to above and shown and described in said Patent No. 637,234, and that when said latch 76 is in its forward position, in contact with the shipper 28, and a drop-bar on one of the warp-threads drops into contact with the metallic roll of said patent the circuit will be completed and the loom stopped, the same as in said patent—that is, the latch 76 forms a part of the electric circuit.

When the latch 76 is moved out of contact with the shipper 28, as shown in Figs. 2 and 6, by the operator, then the electric current is broken, and the shipper 28 will not be operated to stop the loom until said latch 76 is moved into contact therewith, as shown in Figs. 1 and 5.

The advantages of my improvements will

be readily appreciated by those skilled in the art.

My supplemental attachment or mechanism for breaking the electric current is of very simple construction and operation and easily combined with the patented electric warp stop-motion above referred to or with other styles of electric warp stop-motions, and the operator by simply moving the latch 76 outwardly or out of position to be engaged by the shipper 28 when the shipper is moved into position to start the loom can break the electric current and prevent the stopping of the loom by the electric warp stop-motion. When the loom has been run a sufficient length of time to take up the slack warp-threads or for other causes, the operator can then move the latch 76 into engagement with the shipper 28 to render the electric warp stop-motion effective to stop the loom in case of the breaking of a warp-thread.

It will be understood that the details of construction of my supplemental attachment or mechanism and the particular manner of combining the same with the electric warp stop-motion shown in the drawings and above described may be varied, if desired.

Having thus described my invention, what I claim as new, and desire to secure by Letters Patent, is—

1. The combination with an electric warp stop-motion for looms, and the shipper-lever to stop and start the loom, of a spring-actuated latch or lever, adapted to be moved out of engagement with the shipper-lever, and means to hold the latch out of engagement

therewith, to break the electric circuit, and prevent the operation of the electric warp stop-motion to stop the loom, after the shipper-lever is moved to start the loom, substantially as shown and described. 40

2. The combination with an electric warp-stop-motion mechanism, in which the movement of the shipper-lever to start the loom renders effective the electric warp stop-motion to stop the loom, of the shipper-lever, and a device adapted to be moved out of engagement with the shipper-lever, to prevent the operation of the electric warp stop-motion to stop the loom, and into engagement 50 with the shipper-lever to permit of the operation of the electric warp stop-motion to stop the loom, substantially as shown and described.

3. The combination with an electric warp-stop-motion mechanism, in which the movement of the shipper-lever to start the loom renders effective the electric warp stop-motion to stop the loom, of the shipper-lever, and a spring-actuated latch or lever, adapted 60 to be moved out of engagement with the shipper-lever, to prevent the operation of the electric warp stop-motion, to stop the loom, and into engagement with the shipper-lever to permit of the operation of the electric 65 warp stop-motion, to stop the loom, substantially as shown and described.

JOHN A. CLARK.
